SAFETY POLE CAP

Filed Jan. 30, 1928

INVENTOR

C. Nedelec

By *Wm. J. Fowler*,
Attorney

UNITED STATES PATENT OFFICE.

CORENTIN NEDELEC, OF CELTIC, SASKATCHEWAN, CANADA.

SAFETY POLE CAP.

Application filed January 30, 1928. Serial No. 250,577.

This invention relates to new and useful improvements in a safety pole cap for wagons, sleighs, farm implements, etc., and has for its primary object the provision of a pole cap which will serve as a safety attaching means for a neck yoke and thus reduce to the minimum liability of accidents due to runaways.

The invention has for another object the provision of a safety pole cap structure of the character stated, a part of which is carried at all times by the neck yoke and therefore may be removed with the same when unhitching the team, instead of being left 15 on the pole, as in the case of the attaching means now employed and which frequently is damaged by the weather elements when the wagon, sleigh, farm implement, vehicle, or the like, must be left out in the open.

20 A further object of the invention resides in the provision of a safety pole cap of the character set forth in which the parts are of simple and inexpensive construction and the cap is effective in preventing the draft 25 animals from being accidentally released from the pole, owing to breakage of the connection between the neck yoke and the pole or damage thereto, as frequently occurs with the form of connection now in general use 30 and which is rigidly attached to the pole.

A still further object of the invention resides in the provision of a safety pole cap of the character stated, composed of the minimum number of parts, and which includes 35 an L-shaped member carried by the ring of the neck yoke and adapted for removable engagement with the end of the pole.

The invention has for a still further object the provision of a safety pole cap of the character stated which is of simple construction and is automatically locked with the pole and retained in locked engagement therewith by the force of gravity acting on the pole.

45 To the accomplishment of these and re-

lated objects, my invention resides in the construction, combination and arrangement of parts as shall be hereinafter more fully described, illustrated in the accompanying drawing and pointed out in the claims hereunto appended.

The invention will be best understood and can be most clearly described when reference is had to the drawing forming a part of this disclosure.

In the drawing:

The invention is illustrated in use together with the safety cap and a portion of the pole as well as the flared pocket carried beneath the pole and with the neck yoke ring shown 60 in section while the connecting L-shaped member is shown in elevation, in its operative position.

Referring more in detail to the drawing it is to be noted that the safety pole cap includes 65 a forwardly and downwardly flared pocket member 6 secured on the under face of the pole 7 and at the forward end thereof and suitably adapted to the lower leg 8 of the substantially U-shaped cap 9 which is secured 70 on the end of the pole 7 by rivets 10 or in any other well known and preferred manner, with the central or bright portion extended slightly beyond the forward extremity of the pole 7. The upwardly and downwardly 75 flared pocket member 6 is preferably formed of metal and may have its opposite sides flattened as indicated in the drawing, and its forward and rear ends open.

The substantially L-shaped member 11 has 80 the loop or ring 12 provided by bending the member 11 unto itself at the connection of the upstanding short leg 13 thereof with the rearwardly directed long leg 14. The connecting 85 L member 11 is permanently carried by, and suspended on the neck yoke ring 15, as illustrated, and when mounting the neck yoke on the pole, it is simply necessary to insert the long leg 14 in the pocket 6 from the large, 90 open forward end thereof, and then insert

the short upstanding leg 13 through the opening provided therefor in the bottom leg 8 of the substantially U-shaped cap 9, adjacent the bight portion thereof and forwardly of the extremity of the pole 7. It is, therefore, evident that the normally upward pull on the neck yoke ring 15 and the weight of the pole 7 will result in the L member being held in normal position in the pole cap 9, and the upper portion of the pocket 6, as illustrated, thus resulting in the L member serving to assure a safe connection between the neck yoke and the pole 7 at all times while the draft animals are hitched up to the latter. It may also be stated that the L-shaped member may be of increased thickness at the point of crossing of the legs thereof so as to bear properly on the forward end of the pocket 6.

As the construction of this device has thus been set forth in detail; brief reference is now had to its use and modus operandi: The device is assembled as shown in the drawings, with the parts shown in their position by full lines. The mounting is instantaneous and the structure eliminates possibility of the pole 7 dropping away from the neck yoke ring due to breakage or wearing away of metal or leather straps or of hooks as heretofore employed and attached to the pole 7. Whenever it is desired to unhitch the team, the forward end of the pole 7 is held against dropping or is lifted slightly as shown by dotted lines, to permit the L-shaped member 11 to drop out of the opening 16 on to the inclined bottom wall of the pocket member 6, and from the pocket member 6, it may be readily withdrawn. The pole 7 may be permitted to drop at the same time or after the complete removal of the L-shaped member 11 from the pocket member 6.

From the foregoing description taken in connection with the accompanying drawing, it will be manifest that a safety pole cap for wagons, sleighs, farm implements, vehicles, and the like is provided which will fulfill all the necessary requirements of such a device, but as many changes could be made in the above description and many apparently widely different embodiments of my invention constructed within the scope of the appended claims without departing from the spirit or scope thereof, it is intended that all matters contained in the said accompanying specification and drawing shall be interpreted as illustrative and not in a limited sense.

Having thus described my invention what I claim as new and desire to secure by Letters Patent is:—

1. A safety pole cap including a member carried by the ring of the connecting yoke and having an upstanding portion removably engaged in the pole structure from the underside thereof so that the said member is held in the pole structure by the force of gravity acting on the pole structure; said

member having a rearwardly directed leg; and a pocket member firmly secured on the underside of the pole structure to receive said rearwardly directed leg when said member is employed to connect the neck yoke ring with the pole structure; said pocket member having an inclined lower wall to provide a deep, open forward end through which said rearwardly directed leg is inserted and withdrawn.

2. A safety pole cap including a member permanently carried by a neck yoke ring and having a portion removably engaged in a pole structure from the underside thereof and held therein by the force of gravity acting on the pole structure; said member having a rearwardly directed leg; and a pocket member firmly secured on the underside of the pole structure to receive said rearwardly directed leg when said member is employed to connect the neck yoke ring with the pole structure; said pocket member having an inclined lower wall to provide a deep, open forward end through which said rearwardly directed leg is inserted or withdrawn.

3. A safety pole cap including an L member permanently mounted on and suspended from a neck yoke ring and having one portion removably engaged in a pole structure from the underside thereof and held therein by the force of gravity acting on the pole structure; said member having a rearwardly directed leg; and a pocket member firmly secured on the underside of the pole structure to receive said rearwardly directed leg when said member is employed to connect the neck yoke ring with the pole structure; said pocket member having an inclined lower wall to provide a deep, open forward end through which said rearwardly directed leg is inserted and withdrawn.

4. A safety pole cap including the combination with a pole structure and a neck yoke ring; of a connecting member permanently carried by said ring and having a portion removably engaged in said pole structure from the underside thereof and held therein by the force of gravity acting on the pole structure; said member having a rearwardly directed leg; a pocket member firmly secured on the underside of the pole structure to receive the rearwardly directed leg when said member is employed to connect the neck yoke ring with the whole structure; said pocket member having an inclined lower wall to provide a deep, open forward end through which the said rearwardly directed leg is inserted or withdrawn.

5. The combination with a neck yoke ring; of a pole structure including a projecting cap portion of an L member suspended on said neck yoke ring and having an upstanding leg removably engaged in said projecting cap portion of the pole structure from the underside thereof and held therein by the force of gravity acting on the pole structure; said

gravity acting on the pole structure; said member having a rearwardly directed leg; and a pocket member firmly secured on the underside of the pole structure to receive said 5 rearwardly directed leg when said member is employed to connect the neck yoke ring with the pole structure; said pocket member having an inclined lower wall to provide a deep, open forward end through which said rearwardly directed leg is inserted or withdrawn.

10 In testimony whereof I hereunto affix my signature.

CORENTIN NEDELEC.
